UNITED STATES PATENT OFFICE

100,703

DESIGN FOR A METAL BOUDOIR SCREEN

Florence N. Lewis, New York, N. Y.

Application May 27, 1936, Serial No. 62,859

Term of patent 7 years

To all whom it may concern:

Be it known that I, Florence N. Lewis, a citizen of the United States, residing in New York, county of New York, and State of New York, have invented a new, original, and ornamental Design for a Metal Boudoir Screen, of which the following is a specification, reference being had to the accompanying drawing, forming a part thereof.

In the drawing:—

Fig. 1 is a perspective view of the metal boudoir screen showing my new design.

Fig. 2 is a top plan view thereof.

I claim:

The ornamental design for a metal boudoir screen substantially as shown.

FLORENCE N. LEWIS.
